DETACHABLE TAG

Lewis E. Williams, Long Beach, Calif.

Original application August 20, 1934, Serial No. 740,612. Divided and this application June 1, 1936, Serial No. 82,753

6 Claims. (Cl. 40—25)

This invention relates to tags or tickets for attachment to fabrics, particularly tags for use on garments, cloth and the like, to show price, size, the grade of material, or any other desired information.

A broad object of the invention is to provide a tag that can be quickly attached or removed while at the same time resisting accidental removal.

10 Another object is to provide a detachable tag having pointed metal fastening elements so arranged that it is difficult, if not impossible, for an operator to prick himself while attaching or removing a tag or while handling a garment to 15 which the tag is secured.

To the best of my knowledge, it has been the practice heretofore to secure tags to clothing either by sewing the corners of the tag to the fabric with thread and needle or by using a 20 U-shaped wire clip which is attached to the tag during manufacture, the points of the clip being forced through the fabric to which the tag is to be attached and bent back on the other side of the fabric. Sewing is objectionable because 25 it is slow and expensive and also because the thread often breaks, or the end pulls out, thereby permitting the tag to become detached. The tags having wire clips thereon that have been employed heretofore are subject to the criticism 30 that the sharp points are not protected and operators frequently prick their fingers in attaching or removing the tags or in handling the garments to which the tag is to be attached.

In accordance with the present invention, I 35 avoid the foregoing difficulties of the tags heretofore used by imbedding a spring wire in the tag (preferably by forming the tag from two layers of paper or cardboard glued together with the wire positioned between the two layers) and 40 extending one or both ends of the wire out of the tag and pointing the ends of the wire and so curving them that they are directed toward one face of the tag, whereby they are adapted to grip or clamp a fabric against the tag. With this 45 arrangement the point or points of the wire are protected and at the same time a means for securely locking the tag to the fabric is provided.

This application is a division of my application Serial No. 740,612, filed August 20, 1934.

50 In the drawing:

Fig. 1 is a sectional view through one type of tag in accordance with the invention;

Fig. 2 is a perspective view of the wire element employed in the tag shown in Fig. 1;

55 Fig. 3 is a sectional view through a portion of

the tag of the general type shown in Fig. 1 but differing therefrom in detail;

Fig. 4 is a perspective view of the wire element employed in the tag shown in Fig. 3;

Fig. 5 is a sectional view showing still another 5 modification of the general type of tag illustrated in Fig. 1; and

Fig. 6 is a perspective view of the wire element of the tag shown in Fig. 5.

Referring first to Figs. 1 and 2, there is shown 10 a tag 8, which is likewise formed of two layers of pasteboard 9 and 10, respectively, glued together with a portion of a wire element 11 imbedded therebetween. As clearly shown in Fig. 2, the wire element 11 is of irregular outline, 15 comprising straight portions 12, 13, 14, 15, 16 and 17, all of which lie in a common plane and are contained between the two cardboard elements 9 and 10.

Beyond the section 17 there is a straight section 18 extending through the cardboard layer 10, this portion 18 extending at right angles to the plane containing the previously recited sections, and merging into a straight section 19 extending upwardly parallel to the face of the 25 tag but spaced therefrom. This section 19 in turn merges into a straight section 20 which extends through an aperture 21 provided therefor in the tag to the opposite side of the tag, where it merges into another straight section 22, which 30 in turn merges into a straight section 23 extending back through a second aperture 24 in the tag. The section 24 merges into a straight section 19 and merges into a terminal section 26 which is pointed and is juxtaposed to the face 35 of the tag substantially at the intersection of the sections 14 and 15 of the wire. This tag is attached to a fabric by pressing on the exposed section 22 of the wire, thereby moving the point of the wire clear of the tag to permit insertion 40 of the edge of a fabric between the point and the tag. Thereupon, release of the pressure on the section 22 permits the point 26 to be moved toward the tag, thereby gripping the fabric. Obviously the tag may be readily removed by merely 45 repeating the operation described for shifting the point of the wire away from the tag, and withdrawing the fabric.

A simplified form of the tag just described is illustrated in Figs. 3 and 4. In this instance 50 it will be observed that the wire element comprises straight sections 27, 28, 29 and 30, positioned in a common plane and adapted to be imbedded between the two layers of the tag. The wire beyond the straight section 30 is ex- 55

tended substantially at right angles thereto as a straight section 31, out through the edge of the tag, at which point it is coiled as shown at 32, then curved as shown at 33 where it merges into a straight portion 34 extending substantially at right angles to the plane of the tag and passing through a hole 35 provided therefor in the tag. The straight section 34 merges into a straight section 36 substantially parallel to the tag, which merges into the tip 37, which is pointed and normally held against the tag by the inherent resilience of the wire. It will be observed that the tip 37 constitutes a clip which may be opened for the insertion of the edge of a fabric to which the tag is to be attached by pressing the curved portion 33 of the wire toward the tag.

In Figs. 5 and 6, there is shown a modification of the construction described in connection with Figs. 1, 2, 3 and 4 in which the wire, instead of being extended through a hole in the tag, is brought back over the top of the tag. Thus the wire comprises straight sections 40, 41, 42, 43, 44 and 45, all lying in the plane of the tag and imbedded between the two layers of the tag. The end of the section 45 projects through the edge of the tag, beyond which point the wire is coiled, as shown at 46, curved down over one side of the tag to constitute a handle portion 47, then doubled back on itself and extended over the top of the tag as a curved portion 48, which merges into a straight portion 49, which terminates in the tip portion 50. This modification is actuated to displace the point 50 from the tag by depressing the handle portion 47 toward the tag. When pressure on the handle 47 is released, the resilience of the wire engages the pointed end 50 of the wire firmly in a fabric positioned thereunder against the tag.

It will be observed that in all of the modifications of the invention described the pointed tips of the wires are directed toward a face of the tag so that the fabric is clamped firmly between the tip and the tag. Furthermore, this construction makes it almost impossible for an operator to contact the sharp tips of the wires with his fingers either while attaching or removing the tags or while handling garments to which the tags are secured.

Furthermore, in each type of tag described, it will be observed that that portion of the wire which is imbedded between the two layers of the tag extends over a relatively large area within the tag and furnishes a very desirable reinforcement for stiffening the tag.

Although numerous embodiments of the invention have been described, it will be apparent to those skilled in the art that various other changes may be made without departing from the spirit of the invention. The latter is therefore to be limited only as set forth in the appended claims.

I claim:

1. A clothing ticket comprising a tag of sheet material and a spring wire element, one end of which is anchored in said tag and the tip of the other end of which is directed toward a surface of said tag, the intermediate portion of the wire between the anchored end and the tip being normally under tension to yieldably hold said tip against said surface in which a part at least of said intermediate portion of said wire is posi-

tioned in spaced relation from the face of said tag opposite the face against which said tip bears, whereby said tip can be deflected away from said tag by forcing said mentioned part of said wire toward said tag.

2. A clothing ticket as described in claim 1 in which said wire is coiled adjacent its point of emergence from said tag to increase its resiliency at that point.

3. A clothing ticket comprising a tag of sheet material having a spring wire element a portion of which is imbedded therein, at least one end of said wire extending exterior of said tag through one edge of said tag and being bent back over one surface of said tag, the tip of said wire being directed toward said surface of said tag and tensioned to normally bear against said tag, whereby it will grip a fabric positioned thereunder, and a portion of said wire between the tip thereof and the point of emergence from said tag, being extended away from the tag a sufficient distance to be freely movable with respect to the tag and so configured that deflection of that portion raises the tip away from the surface of the tag.

4. A tag of sheet material in combination with means for attaching the tag to a fabric surface comprising a length of spring wire a portion of which is imbedded in the tag and curved to enclose a substantial area therewithin, one end of said wire extending beyond said tag through one edge thereof, thence back over one face of said tag and then being doubled back on itself and extending across the end of the tag to a point spaced substantially from the plane of the tag, and thence curved to bring the tip of the wire in contact with said other face of the tag, whereby movement of said doubled-back portion of the wire toward said tag displaces the tip away from said other face of said tag.

5. A tag of sheet material in combination with means for attaching the tag to a fabric surface, comprising a length of spring wire a portion of which is imbedded in said tag, said wire extending exterior of said tag through one edge thereof, thence back along one face of said tag, thence through a hole in said tag provided therefor, said wire being given a return bend on the opposite side of said tag to bring said tip against said other face of said tag.

6. A tag of sheet material in combination with means for attaching the tag to a fabric surface, comprising a length of spring wire a portion of which is imbedded in the tag and bent to define substantially a closed figure therewithin, one end of said wire being projected through one face of said tag to a point spaced therefrom, thence in a straight line parallel to the plane of said tag, thence perpendicular to and extending through said tag, thence again in a direction parallel to said tag and substantially parallel to said first parallel portion, thence to and through said tag to a point spaced from the plane of the tag on the opposite side thereof, the tip of said wire being curved back toward and contacting with said other face of said tag, said tag being provided with apertures for freely receiving said wire at the points where it passes therethrough, whereby pressure on said second parallel portion of said wire displaces said tip from the face of said tag.
